UNITED STATES PATENT OFFICE.

YUBA T. GOODWIN, OF BROOKLINE, MASSACHUSETTS.

DESIGN FOR A TOY.

48,820.

Specification for Design.

Patented Apr. 4, 1916.

Application filed December 3, 1914. Serial No. 875,379. Term of patent 14 years.

To all whom it may concern:

Be it known that I, YUBA T. GOODWIN, a citizen of the United States, and a resident of Brookline, in the county of Norfolk and State of Massachusetts, have invented a new, original, and ornamental Design for a Toy, of which the following description in connection with the accompanying drawings, is a specification.

In the drawings:—Figure 1 is a perspective view of a toy in seated position having the design of my invention; and Fig. 2 is a

perspective view thereof in standing position.

What I claim is:

The ornamental design for a toy, as shown.

In testimony whereof, I have signed my name to this specification, in the presence of two subscribing witnesses.

YUBA T. GOODWIN.
